DESIGN FOR A DYNAMO-ELECTRIC MACHINE

Gordon R. Anderson, Beloit, Wis., assignor to
Fairbanks, Morse & Co., Chicago, Ill., a corpo-
ration of Illinois

Application April 23, 1945, Serial No. 119,156

Term of patent 14 years

(Cl. D26—1)

To all whom it may concern:

Be it known that I, Gordon R. Anderson, a citizen of the United States, residing at Beloit, in the county of Rock and State of Wisconsin, have invented a new, original, and ornamental Design for a Dynamo-Electric Machine, of which the following is a specification, reference being had to the accompanying drawing, forming part thereof.

In the drawing:

Fig. 1 is a view in elevation at the forward end of a dynamo-electric machine, showing my new design;

Fig. 2 is a view in side elevation, of the machine;

Fig. 3 is an end elevation thereof, at the opposite or rear end of the machine; and

Fig. 4 is a side elevation of the machine, as viewed oppositely to the side view of Fig. 2.

I claim:

The ornamental design for a dynamo-electric machine, as shown.

GORDON R. ANDERSON.
